DESIGN FOR A BOTTLE

Owsley Brown, Louisville, Ky., assignor to Brown-
Forman Distillery Company, Louisville, Ky., a corporation of Delaware

Application March 12, 1940, Serial No. 90,860

Term of patent 14 years

To all whom it may concern:

Be it known that I, Owsley Brown, a citizen of the United States, residing at Louisville, county of Jefferson, and State of Kentucky, have invented a new, original, and ornamental Design for a Bottle, of which the following is a specification, reference being had to the accompanying drawing, forming a part thereof.

and
Figure 5 is a top plan view of the bottle.
I claim:
The ornamental design for a bottle, as shown.

OWSLEY BROWN.
